IGNITION SYSTEM FOR INTERNAL COMBUSTION ENGINES

Edgar M. Major, New York, N. Y.

Application November 14, 1940, Serial No. 365,718

7 Claims. (Cl. 123—148)

This invention relates to improvements in ignition systems for internal combustion engines.

The primary object of this invention is the provision of an improved ignition system for internal combustion engines, which is relatively simple in construction; automatic in operation, economical, and which will do away with the complicated features of present day internal combustion engine ignition systems using such features as timing gear, spark plugs, distributors, etc.

A further object of this invention is the provision of an improved ignition system which will automatically supply a spark to the compressed combustion charge immediately after crank shaft throw of the piston has passed dead center; the construction being such that premature firing is impossible.

Other objects and advantages of this invention will be apparent during the course of the following detailed description.

In the accompanying drawing, forming a part of this specification, and wherein similar reference characters designate corresponding parts throughout the several views.

Figure 1 is a cross section taken through the cylinder of an internal combustion engine, showing the association of my improved electrodes during the compression stroke in the cylinder.

Figure 2 is the view similar to that shown in Figure 1, but with the electrodes in sparking relation immediately after the throw of the piston has passed top dead center.

Figure 3 is a plan view of my improved piston electrode.

Figure 4 is a plan view of the firing pin of the improved piston electrode.

Figure 5 is a diagrammatic view showing the wiring arrangement for the electrodes.

In the drawing, wherein for the purpose of illustration is shown only preferred embodiment of the invention, the letter A may generally designate an internal combustion engine, which includes one or more cylinders B; a piston C operating therein; a crank shaft D and connecting rod E. My improved ignition system includes cylinder attached and piston attached electrodes F and K disposed in a wiring circuit L which includes the usual transformer coil M having primary and secondary windings as shown in Figure 5 of the drawing; the continuous vibrating primary circuit having disposed therein a battery N and vibrator T.

In addition to simplicity and economy of operation, doing away with such complicated fea-

tures of conventional ignition systems as spark plugs, timing gear, distributors, etc., the improved electrode arrangement in the cylinder and upon the piston is of such nature that the spark for the combustion charge will fire the charge at precisely the right moment; immediately after the throw of the piston has passed top dead center. This is accomplished because the electrode upon the piston is normally positioned in a non-sparking relation with respect to the other electrode, but due to its inertia as the piston passes top dead center, the firing pin thereof will move into sparking relation with respect to the stationary electrode, for firing the compressed charge.

The stationary electrode F preferably includes a metallic externally screw threaded shell or plug 10, internally provided with insulation body material 11, of any approved nature, which may support axially thereof the electrode pin 12. The top of the cylinder, designated at 13, is preferably provided with an internally screw-threaded opening 15, axially aligned with respect to the cylinder chamber, in which the externally screw threaded shell 10 of the stationary electrode detachably fits. The shell 10 is preferably provided with a reduced nut head 20, integral therewith, for receiving a wrench in order to adjust the stationary electrode in proper position in the top of the cylinder block. The stationary electrode pin 12 is of course provided with wire clamping nuts 25 thereon, as shown in Figures 1 and 2 of the drawing. The plug or shell 10 can be adjusted so as to position the firing point of the stationary electrode pin 12 at about the center of the compression compartment in the top of the cylinder, as shown in Figure 2 of the drawing.

Referring to the piston carried electrode K, the same includes a cup shaped support 30, preferably of metal, which is provided with an externally screw threaded portion 31 on the upper end thereof, adapted to detachably fit in a screw threaded socket 32 provided in the top wall 34 of the piston C, as shown in Figures 1 and 2 of the drawing. The cup shaped support 30 provides a compartment 37 which opens upwardly, and at the top it is provided with a nut flange 38, adapted to receive a wrench or other tool in order to apply the cup shaped support 30 in position. The compartment 37 of this support 30 receives a slidable electrode member 40, consisting of a head or disc 42 which fits in the compartment 37 for sliding, and an upwardly extending axial firing

pin portion 43, which is pointed for sparking cooperation with pin 12 above described.

The support 30 is internally provided with a screw threaded portion 58 adapted to detachably receive an externally screw-threaded apertured disc 52. In the compartment 37 between the bottom wall of the cup shaped support 30 and the adjustable closure 52, the head portion 42 of the electrode is adapted to slide back and forth. The disc portion 42 of the electrode is provided with suitable ports 58 so that pressure on opposite sides may be equalized as the electrode slides back and forth in the cup 30. Similarly, the closure 52 is provided with ports 60 so that air may exhaust from the compartment 37 as the firing pin or electrode 40 moves upwardly, due to its momentum, after the piston throw has passed dead center.

The operation of the ignition system will be apparent from the foregoing. Normally, the parts are positioned as shown in Figure 1. By gravity, the movable piston supported electrode 40 of this disc portion 42 rests on the bottom wall of the cup shaped shell 30, and the point end of the firing pin 43 is in a non-sparking relation with respect to the stationary firing pin 12. As the piston moves upwardly to compress the firing charge in the cylinder the movable electrode 43 will retain the position shown in Figure 1 until the throw of the piston C has reached top dead center. At this time, due to inertia, the movable electrode 40 will continue its movement while the piston S starts to descend, and the firing pins will be brought into sparking relation and thus explode the compressed charge.

The opening 13 in the cylinder top is of such size that the piston supported electrode can be removed or adjusted through said opening.

My invention is applicable to radial and revolving engines as well as to the type of engine herein illustrated and described. The dynamics of these engines are such that my ignition system will operate properly, although gravity does not play the part in controlling the position of the electrodes for the top pistons of such engines as it does in the type of engine herein illustrated.

Various changes may be made in the form of invention herein shown and described, without departing from the spirit of the invention or the scope of the following claims.

I claim:

1. An electrical ignition device for internal combustion engines comprising a stationary cylinder supported electrode insulated therewith, and a movable piston supported electrode so mounted that it will be brought into sparking relation with respect to stationary cylinder supported electrode only after the piston throw has passed top dead center.

2. In an electrode arrangement for internal combustion engines ignition systems the combination of a piston, and an electrode freely movable upon the piston and so positioned that by gravity it will normally assume a non-sparking

position upon the piston with respect to a companion electrode.

3. In an ignition system for internal combustion engines the combination of a cylinder, a stationary electrode supported by the cylinder, a piston, a crank shaft having a throw, a connecting rod connecting the throw with the piston, and a movable electrode freely movably supported upon the piston and adapted by gravity normally to assume a non-sparking position with respect to the stationary cylinder supported electrode until the throw of the piston has passed top dead center when due to momentum the movable piston supported electrode will move into sparking relation with the stationary electrode.

4. An article of manufacture an electrode for internal combustion engines comprising a supporting receptacle having a compartment therein, and a movable electrode having a sparking point exteriorly of the receptacle and a portion in the receptacle freely slidable back and forth without restraint in either direction.

5. An ignition system for internal combustion engines comprising a cylinder supported stationary electrode insulated from the cylinder, a piston supported electrode in movable electrical conducting relation with the piston and by gravity normally positioned in an inoperative sparking relation with respect to the stationary electrode, 25 said movable electrode on the piston being freely slidable so that as the throw of the piston passes top dead center the said movable electrode due to its momentum will move into sparking relation with respect to the stationary electrode of the cylinder.

6. In an electrode for internal combustion engines the combination of a cup shaped receptacle of conductive material having an external screw threaded portion thereon, a removable cover for the compartment of the receptacle having air passage ducts therethrough, and a firing electrode including a disc portion in the cup shaped receptacle and a pin portion slidable through said cover, said disc portion of the electrode having ports therein to equalize pressure at each side thereof as it moves back and forth within the cup shaped receptacle.

7. In an electrode for internal combustion engines the combination of a cup shaped receptacle of conductive material having an external screw threaded portion thereon, a removable cover for the compartment of the receptacle having air passage ducts therethrough, and a firing electrode including a disc portion in the cup shaped receptacle and a pin portion slidable through said cover, said disc portion of the electrode having ports therein to equalize pressure at each side thereof as it moves back and forth within the cup shaped receptacle, said electrode being freely slidable back and forth within said receptacle without any positive urge in either direction except through gravity.

EDGAR M. MAJOR.
